[57] CLAIM

The ornamental design for a fragrance frame, as shown and described.

DESCRIPTION

FIG. 1 is a top plan view of a fragrance frame showing our new design;

FIG. 2 is a bottom plan view thereof;

FIG. 3 is a front elevational view thereof;

FIG. 4 is a left side elevational view thereof;

FIG. 5 is a right side elevational view thereof; and,

FIG. 6 is a back elevational view thereof.

The cross-hatching represents fabric and is understood to extend uniformly throughout the areas represented.
